ACOUSTIC GRILLE CLOTH

Filed Feb. 17, 1932

INVENTOR.

ALFRED T. ABBOTT,
BY
William J. Jackson.

ATTORNEY.

UNITED STATES PATENT OFFICE

ALFRED T. ABBOTT, OF PHILADELPHIA, PENNSYLVANIA

ACOUSTIC GRILLE CLOTH

Application filed February 17, 1932. Serial No. 593,555.

This invention, generally stated, relates to the weave of fabrics and has more particular relation to the fabrication of a cloth particularly adapted for use in connection with grilles of radios.

As at present practiced the grille cloth of a radio is fabricated in a fashion calling for an ordinary weave with ordinary yarn. Practice has demonstrated that the air waves from the loud speaker impinge upon conventional grille cloths in such manner as to muffle or deaden the tones desired to be employed. Practical demonstration has brought forward the fact that it is because of the plain or net woven fabric that these deadened or muffled tones result.

The leading object of the present invention may be said to reside in the providing of a loosely woven fabric for the grilles of radios designed to accentuate the acoustic properties of a radio emanating through a grille cloth as positioned before a loud speaker so as to mellow and smooth out, as it were, the sound waves of the instrument.

A further object of the present invention is to provide a grille cloth of the character stated made up of a cotton warp and two different kinds of wefts or fillings wherein one filling is silk-like to add luster to the cloth and makes a loose weave with the warp ends, and wherein the other weft or filling is a specially constructed yarn having knot-like protuberances thereon, which yarn functions to pull the loose weave threads together so that when the yarn is floated upon the back of the fabric an embossed effect is obtained upon the front of the fabric, and when the yarn is floated upon the front of the fabric a similar embossed effect appears upon the reverse side of the fabric, whereby the warp ends are prevented from slipping so that the embossed effect is maintained in fixed position.

A further object of the present invention is to provide a grille cloth of the character stated in which interstices or openings occur between adjacent embossed portions of the fabric, whereby loud speaker tones may pass smoothly through these openings between embossed portions of the cloth in contradis-

tinction to having the loud speaker tones impinge directly upon an ordinary plain or knit woven surface.

With the above and other objects in view, the invention consists of the novel construction hereinafter described and finally claimed.

The nature, characteristic features and scope of the invention will be more fully understood from the following description taken in connection with the accompanying drawing forming part hereof, and in which:

Fig. 1 is a face view, more or less diagrammatically illustrated, of a fabric embodying the invention;

Fig. 2 is a view in cross section of Fig. 1, drawn to an enlarged scale;

Fig. 3 is a fragmentary view more or less diagrammatically illustrated upon an enlarged scale of a portion of the fabric shown in Fig. 1;

Fig. 4 is a view of a so-called knot-yarn having spaced knot-like protuberances thereon; and

Fig. 5 is a view in elevation of a radio illustrating a grille cloth embodying the invention applied thereto.

For the purpose of illustrating my invention I have shown in the accompanying drawing one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the fabrication of my grille cloth according to the present invention I weave a very loose fabric made up of cotton warps and two different kinds of wefts or fillings. The warp of the fabric comprises cotton threads. The wefts or fillings comprise first a silk-like filling which makes a loose weave with the cotton warp ends, and second, a filling comprising specially constructed knot-yarn that acts like stitches and pulls the loose weave threads together to form an embossed design. This knot-yarn is floated upon the

back of the fabric to produce an embossed effect upon the front of the fabric and is floated upon the front of the fabric to produce the same embossed effect upon the reverse side of the fabric. The rough or knot-yarn prevents slipping of the cotton warp ends so that a permanent or non-shifting design is secured.

Referring to the drawing in detail, and with more especial relation to Figs. 1 to 4, the reference numeral 10 designates the cotton warps of the fabric. The wefts form the filling. This filling comprises silk or artificial silk threads 11 in order to provide luster or sheen to the completed fabric. The wefts 11 are fabricated to make a loose weave with the cotton warp ends. Paralleling the wefts 11 but spaced therefrom are other wefts 12 to complete the filling. These wefts 12 comprise strands of so-called knot-yarn which is not obtained in the open market in general business transactions but has to be specially selected. As best seen in Fig. 4, this yarn is roughened and is provided at regular intervals, in practice about one inch apart, with knot-like protuberances 13. The function of the knot-yarn is that of pulling the loose-weave together as it is alternately floated upon the back and front of the fabric to provide an embossed effect both upon the front and the back of the fabric. The knot-like protuberances of the floated yarn serve to prevent slipping of the warp ends, thereby providing the embossed design effect. While the fabric is loosely woven, it is strengthened by the knot yarn so that the warp, as designed, may open up and allow the tones of the loud speaker to pass freely and smoothly through the interstices or openings 14, see Figs. 1 and 3, which are arranged between adjacent embossed portions of the fabric. In this connection it is to be noted that the back of the grille cloth as fabricated provides an uneven surface so that the tones from the loud speaker do not impinge upon a flat grille cloth surface as in the case of an ordinary plain or net woven fabric, but on the contrary impinge upon a roughened or uneven surface thereby sufficiently breaking up the tone waves to mellow and soften them.

Referring now to Fig. 5, the reference numeral 15 designates a radio of any desired type provided with a grille cloth 16 fabricated in accordance with the present invention.

I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

What is claimed is:

1. A loosely woven grille cloth for radios, said cloth having an embossed design secured against displacement by means of a specially constructed knot-yarn filling. 70

2. A loosely woven grille cloth for radios, said cloth having an embossed design arranged both upon the back and the front of said cloth and secured against displacement by means of a specially constructed knot-yarn filling. 75

3. A loosely woven grille cloth for radios, said cloth having an embossed design arranged both upon the back and the front of said cloth and secured against displacement by means of a specially constructed knot-yarn filling, there being interstices or open spaces between adjacent embossed portions of the cloth. 80

4. A loosely woven grille cloth for radios comprised of cotton warps and a filling made up of silk-like threads and a knot-yarn of which the former makes a loose weave with the warp ends and of which the latter functions to pull the threads of the loose weave together when floated upon the back of the fabric to provide an embossed design on the front of the fabric and when floated upon the front of the fabric provide a similar embossed effect upon the reverse side of the fabric. 85

5. A loosely woven grille cloth for radios comprised of cotton warps and a filling made up of silk-like threads and a knot-yarn of which the former makes a loose weave with the warp ends and of which the latter functions to pull the threads of the loose weave together when floated upon the back of the fabric to provide an embossed design on the front of the fabric and when floated upon the front of the fabric provide a similar embossed effect upon the reverse side of the fabric, said knot-yarn serving to prevent slipping of said warp ends to maintain said embossed design in relatively permanent position. 100

6. The herein described manner of making a grille cloth for radios which consists in taking cotton warps and two different kinds of wefts or filling, one being silk-like and the other a rough yarn, and weaving the silk-like wefts with the cotton warp ends to provide a loose weave and causing said rough yarn to pull said loose weave together by floating said yarn upon the fabric back to provide an embossed effect on the fabric front, and causing said yarn to float upon the fabric front to provide a similar embossed effect upon the reverse side of the fabric, said rough yarn serving to prevent slipping of the warp ends. 105
